(57) **CLAIM**

The ornamental design for a shoe, as shown and described.

DESCRIPTION

FIG. 1 is a top right front perspective view of a first embodiment of a shoe showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof, in which the top plan view is identical for FIGS. 8-11 and FIGS. 12-17;

FIG. 7 is a bottom plan view thereof, in which the bottom plan view is identical for FIGS. 8-11 and FIGS. 12-17;

FIG. 8 is a top right front perspective view of a second embodiment of a shoe showing our new design;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top right front perspective view of a third embodiment of a shoe showing our new design;

FIG. 14 is a front elevational view thereof;

FIG. 15 is a rear elevational view thereof;

FIG. 16 is a left side elevational view thereof;

FIG. 17 is a right side elevational view thereof;

FIG. 18 is an enlarged portion view taken from encircled portion labeled FIG. 5; and,

FIG. 19 is an enlarged portion view taken from encircled portion labeled FIG. 19 in FIG. 5.

The broken lines in the drawings indicate portions which form no part of the claimed design.

1 Claim, 18 Drawing Sheets
